UNITED STATES PATENT OFFICE.

WILLIAM D. WILCOX, OF IDAHO FALLS, IDAHO.

PROCESS OF MAKING COMBUSTIBLE GAS.

Application filed April 1, 1921. Serial No. 457,811.

As is well known, gas is produced by heating bituminous coal in an enclosed coke oven or gas retort so that the volatiles of the coal are driven off. This is known as coal gas.

Gas is also produced by passing steam through a body of carbon, which in general practice is anthracite coal or coke, which has been brought to a high temperature by previous air blasting. This is known as water gas.

It is the purpose of my invention to secure the complete gasification of bituminous coal in one continuous operation, producing a combined coal and water gas, with the least possible loss of heat in the operation, and consequently the largest possible output of gas from a given weight of fuel. There are in existing processes substantial losses of heat which it seems possible to avoid. In driving the volatile gases from coal by means of heat passed by conduction through walls of substantial thickness and relatively poor conductivity and from the inner surface of these walls through coal which is itself a poor conductor, it is necessary to generate by the burning of bench fuel, a much greater quantity of heat than is actually realized in changing the volatiles of the coal from the solid to the gaseous state. Not more than a small proportion of the total heat is utilized in ordinary practice.

Where the coke is used to produce water gas in a detached generator, the sensible heat imparted to it in the carbonizing process is removed by quenching and lost. In the production of water gas it is necessary to bring the cold fuel by air blasting to a temperature substantially in excess of the minimum temperature at which the oxygen released by the decomposition of the water molecule H_2O will unit with the adjacent carbon predominately as carbon monoxide (CO) rather than as carbon dioxide (CO₂). From this necessity, it follows that whatever may be done by increasing the blast pressure or reducing the height of the fuel bed, there is during the latter portion of the air blast a loss of fuel value not only as sensible heat in the escaping blast gases, but by the presence in the blast gases of a large proportion of the carbon monoxide. This requires the burning of a greater weight of fuel and the production of a greater quantity of heat than is utilized to decompose the steam.

I am aware that apparatus has been in-

vented in which regenerator chambers filled with checker brick are heated to a high temperature by the sensible heat of the escaping blast gases and by the burning therein of the carbon monoxide content, and through which the water gas and steam are made to pass during an intermediate period in the process of generation so that much of this heat is made useful in increasing the make of water gas. A considerable gain in thermal efficiency has been secured by the use of this apparatus, but it has certain disadvantages when the fuel used is bituminous coal which is the purpose of my invention to eliminate.

In this apparatus blasting is upward, the air being admitted under pressure below the grate of the generator. The hot products of combustion pass upward through the layer of green or freshly charged fuel upon the upper surface of the fuel body and carry forward into the regenerator to be destructively consumed therein during the blasting period a large proportion of the hydrocarbon volatiles of the coal. During the run period, steam admitted below the grate of one generator passes upward, through the regenerators, into the upper portion of a second generator and then downward through the body of incandescent fuel, the resulting water gas being withdrawn quite hot from a level a little above the grate in the second generator.

It is claimed as a merit of the process attained in this apparatus that the hydrocarbon gases and tarry vapors carried forward by the current of water gas are, by contact with the hot carbon in the lower portion of the second generator, broken up into hydrogen and carbon monoxide so that the gas can be used with very little effort toward the removal of the tar. But where an enriched gas containing a greater number of heat units in a given volume is desired this is not an advantage, but rather the reverse.

The apparatus which I have designed is somewhat similar to that just described, consisting of twin generators, discharging into corresponding regenerators which are cross connected at the top, but with such changes in the arrangement of parts, and in the method of operation, as to produce a very different product. The air is admitted not below the grates, but at a level intermediate between the upper surface of the fuel body and the grate. The air does not pass up-

ward, but downward. The passages conducting the blast gases from the generators into the regenerators are not above the upper surface of the fuel but just above the grates. The conserved gases, instead of passing downward through a body of highly heated coke to an outlet just above the grate are withdrawn through an outlet above the level of the fresh coal. Only a very small proportion of the rich hydrocarbons in the coal given off during the blasting are decomposed by contact with hot carbon during the generation period.

In order to minimize the destruction of the rich coal gases given off from the material in the upper levels of the generator chamber during the air blasting period, as a result of precedent heating, the conserved gas outlets may be left partly open; the openings being controlled by the observation of pressure gauges indicating the pressure at the air inlet and gas outlets, so that the pressure of gas generation will balance the blast pressure and permit no air to pass upward and little or no coal gas to pass downward below the level at which air is admitted.

The hydrocarbons are distilled off by the upward passage of the water gas during the steam run period, hence are little decomposed and the sensible heat of the hot water gas which as a usual practice is removed by cooling, is thus made useful, taking the place of and accomplishing the work done by a much larger quantity of heat generated by the burning of bench fuel in the usually employed method of carbonizing coal. This sensible heat acts with greater efficiency because the gas which imparts it to the coal passes upward in direct contact with the coal in a fairly uniform volume throughout the horizontal cross section of the coal body.

The process and the design of the apparatus can be better understood by reference to the accompanying drawings. Figure 1 shows a vertical elevation viewed from one end. Figure 2 is a vertical cross section of the apparatus. Figure 3 is a horizontal cross section taken at X—X as shown by Figure 2 but not showing the fuel and checker work. A¹ and A² are gas generators. These are filled nearly to the top with bituminous coal introduced from time to time through charging doors, J¹ and J². During the blasting period, air is admitted through air inlets C¹ and C² and smaller air inlets 1 and 2 admitting to generators A¹ and A² respectively. At this time gas outlets D¹ and D² are closed. Waste or blast gas outlet E is open. The combustion products pass downward and through passages L¹ and L² into the regenerator chambers B¹ and B² where they are fully burned by air entering at H² and H³. A limited quantity of air entering during

this period below the grates G¹ and G² at H¹ and H⁴ secures a complete combustion of the generator fuel to ash. When the desired temperature has been attained by blasting, the air is shut off. Steam is then admitted at both C¹ and C² through M¹ and M² to 70 purge the apparatus. One steam inlet is then closed. In one period this is M², M¹ being open, E is closed, gas outlet D² is opened, steam entering at C¹ under the pressure supplied by its generation in a boiler passes down through the body of fuel in A¹ through L¹, up B¹, across, down B², through L², into A², up A² and through the body of fresh or uncarbonated fuel above the level of C² in A² to which it imparts a large portion of its 80 sensible heat driving off the volatiles and carrying them forward through D² to be later removed in the usual way or to remain as enriching gases.

In the succeeding generation period following reblasting, steam may be admitted at C² and taking a reverse direction of travel the resulting gases will be withdrawn through D¹ thus maintaining substantially uniform conditions in the two generators. 90 Doors F¹ and F² are provided to permit the cleaning of the grates and removal of dust which may drop out of the blast gases in the regenerators. K¹ and K² are manholes which may be periodically opened to permit 95 a replacement of burned out checker brick. The process may be carried out in apparatus of somewhat different design, as, for example, the generators may be detached and of the more usual cylindrical form discharging 100 through pipes into corresponding detached regenerators. It is not my purpose to restrict myself to a particular design of apparatus in carrying out the process.

I claim:

The herein described process of generating coal and water gas by admitting air for blasting at an intermediate level to a body of coal contained in each of two generators, and thereby heating the fuel to incandescence, passing the blast gases downwardly and into corresponding regenerators, adding additional air for the combustion of the blast gases therein, alternately thereafter admitting steam to one of the two generators at the same level at which air was previously admitted, passing the steam downwardly through the incandescent fuel to form water gas, passing the water gas into and up the adjoining regenerator, across, and down the second regenerator and thereby superheating the water gas, passing the superheated water gas into the second regenerator, and then upwardly through a body of fuel having a 110 layer of uncarbonized coal to a gas outlet above the coal, whereby mixed coal and water gas is produced.

WILLIAM D. WILCOX.
